CAR ROOF

Douglas J. Baillie, Montreal, Quebec, Canada

Application February 26, 1944, Serial No. 523,989

6 Claims. (Cl. 108—5.4)

1

The invention relates to metal car roofs of the type wherein self-supporting roof sheets extend from side to side of the car and are rigidly secured along their adjacent margins by upstanding flanges that function as carlines and have members depending therefrom for supporting an underlying insulating lining.

The principal object of the invention is to provide a roof structure having great strength throughout the carline portions thereof and novel means for strengthening the eaves portions of the roof sheets.

Another object is to provide an improved roof structure having great strength and comprising a minimum number of component parts; these parts being substantially the roof sheets and seam covers.

A further object is to provide an improved roof structure wherein the carline portions do not require separate rigidifying strips intermediate the adjacent upstanding flanges of adjoining roof sheets.

A further object is to provide a roof structure not requiring separate mounting or connecting members to support the insulating lining and lining supporting purlines.

Another object is to provide an improved roof structure wherein the eaves portions of the roof sheets do not require separate supporting members affixed to the side plates of the car.

A further important object of the invention is to provide an improved roof structure having a minimum number of component parts, resulting in economy of manufacture of the roof and economy of application of the roof to the car.

Still another object is to provide a roof structure wherein the roof sheets and seam covers may be made of the same gauge of metal, eliminating the necessity for using a heavier metal sheet for the seam cover than used in the roof sheets.

Other objects, advantages and capabilities of the invention will appear from the following description of the preferred embodiment thereof, taken in conjunction with the accompanying drawings, in which:

Figure 1 is a fragmentary plan view of the car roof structure.

Fig. 2 is a fragmentary transverse sectional view of substantially one half of the structure shown in Fig. 1, taken along line 2—2 of Fig. 1.

Fig. 3 is an enlarged fragmentary sectional view taken along line 3—3 of Fig. 2.

Fig. 4 is an enlarged fragmentary plan view of the eaves portions of adjoining roof sheets, with the seam cover removed in order to show the

2

method of forming the marginal reinforcements of the roof sheets.

Fig. 5 is an enlarged fragmentary plan view of the roof structure adjacent the seam cover, adapted to show the method of mounting the insulating lining upon the roof.

Fig. 6 illustrates an alternate method of forming the longitudinal margin of the roof sheet.

Referring to the drawings, the roof sheets are indicated as A, the side plates as B, the seam covers as C, the purlines as D and the insulating lining as E. The roof sheets may span the car from side plate B to side plate B and may have their opposed end margins rigidly secured to adjacent side plates. The side plate B may comprise a metal Z-bar having a horizontal web, an inwardly disposed upstanding flange and an outwardly disposed depending flange.

The sheet A may be provided with opposed side marginal upstanding flanges 10 and opposed end marginal depending flanges 12. The flange 10 and its associated portions may comprise an upwardly bent portion 14 having a re-bend at its upper extremity, an integral downwardly extending portion 16 in parallel abutting engagement with the portion 14 and a lateral flange portion 18 in parallel underlying abutting engagement with the adjacent plane portion of the sheet A. It will be seen that the flange 10 comprises a double thickness as compared with the conventional single thickness, thereby adding strength to the flange 10. The depending flange 12 may be provided adjacent its lower extremity with a re-bend and an upwardly extending wall 20 in abutting engagement with the flange 12 adapted to provide eaves flanges on the sheet A having double thickness. The lower marginal portion of the flange 12 may be vertically disposed and may be connected with the major plane portion of sheet A by an arcuate portion extending laterally of the sheet, this arcuate portion being preferably formed on a large radius and both the flange 12 and the wall 20 being in abutting relationship throughout the arcuate portion.

The free edge of the flange portion 18 and the free edge of the wall 20 may be slightly curled in a direction away from the adjacent plane portion of the sheet A, in order to prevent chafing therebetween. The flange 18 may be provided along its length with spaced apart downwardly depressed portions 22, each having a shelf portion 24 in underlying spaced relation with the adjacent plane portion of the sheet A. The portion 24 may be connected with the flange 18 by means of a wall 26 and walls 28 integral with the

flange 18. The portion 24 may have an aperture 29 of key-hole configuration with a circular portion 30 and an opposed portion 32 of reduced size rectangular in shape.

The seam cover C may comprise a sheet metal member of inverted U-shaped configuration including parallel spaced apart vertical walls 34-34 integrally joined at their upper extremities and having opposed lateral flanges 36 adjacent their lower extremities. The seam cover C is adapted to embrace the adjacent flanges 10-10 of adjoining sheets and may be affixed thereto by rivets 38. The depressed portions 22 may be located coincident with the location of the purlines D and purlines D may be secured in underlying engagement with the portions 24 by means of vertically disposed carriage bolts 40 and fastening nuts. The head of the bolt 40 may be upwardly inserted through the circular portion 30 of the aperture 29, after which the bolt may be bodily moved in a lateral direction until the square shouldered portion of the carriage bolt registers with and will be held against axial movement by the portion 32 of the aperture 29 while the fastening nut is being tightened on the bolt.

The eaves flanges 12 of the sheet A may be riveted to the upstanding flange of the adjacent side plates B-B by means of the usual rivets 42. The corner portions of the sheet A may be suitably coped out before forming the sheet whereby the ends of the flanges 18 may terminate adjacent the walls 20-20, as best shown in Fig. 4. While I have shown spacing between the end of the flange 18 and the adjacent free edge of the wall 20 I contemplate having the end of the flange 18 butt the edge of the adjacent free edge of the wall 20 and connecting them as by welding, if this additional strength is desired. While the end of the seam cover C may be of conventional tapered design I prefer to maintain a constant depth throughout the length of the seam cover in order to use fastening rivets throughout the arcuate end portions of the seam covers, in the interest of adding strength to the seam structure adjacent the eaves.

As best shown in Fig. 6, I contemplate an alternate method of forming the opposed longitudinal edges of the sheet A, comprising an upstanding wall portion 44, a re-bend at the upper extremity of wall portion 44, a downwardly extending wall portion 46 in parallel abutting engagement with and extending a substantially uniform depth below said wall portion 44. The lower marginal portion of the wall portion 46 may be provided with a laterally extending flange 48 in substantially uniformly spaced relation with the adjacent plane portion of the sheet A. This alternate method will eliminate the necessity for forming the spaced apart depressed portions 22 and will increase the supporting strength of the longitudinal margin of the sheet A by increasing the amount of metal in vertical disposition. I further contemplate the structure shown in Fig. 6, without the laterally extending flange 48, for cars not requiring the insulating lining E, in which case the wall portion 46 may be of optional depth throughout the width of the car according to predetermined load supporting strength desired. Where the wall portion 46 is used without the lower flange 48, the adjacent abutting wall portions 46-46 of adjoining sheets may be secured below the roof line by horizontally disposed rivets extending through said abutting wall portions.

The "carline portions" referred to herein is

intended to mean that portion of the roof coincident with the location of the seam covers C.

It will be understood that the double-walled flange of the longitudinal margin of the roof sheet need not be on both longitudinal margins of the sheet, as one margin may comprise the single-thickness upwardly turned flange of the prior art and the opposed flange may be of the double-thickness structure as shown in the drawings, without departing from the scope of my invention. It will further be evident that that portion of the flange 10 which provides the double-thickness may be disposed substantially on the upper surface of the roof sheet instead of the reverse, as shown in the drawings.

15 I claim:

1. A car roof including a plurality of adjacent laterally disposed roof sheets provided with opposed longitudinal upstanding marginal flanges and a seam cover adapted to secure the said flanges of adjacent roof sheets in affixed relationship; one of said flanges being re-bent to form a downwardly extending wall in adjacent parallel

20 relation therewith adapted to provide a double-thickness flange, said wall being disposed in a vertical plane and being vertically coextensive with the flanges to add load supporting value to the flanges.

2. A car roof including a plurality of adjacent laterally disposed roof sheets provided with opposed longitudinal upstanding marginal flanges and a seam cover adapted to secure the flanges of adjacent roof sheets in parallel adjacent fixed

25 relationship; one of said flanges being re-bent to form a downwardly extending wall in adjacent parallel relation therewith, said wall being disposed in a substantially vertical plane and extending below the major portion of the roof sheets, adapted to function as a tension member to add load supporting value to said one of said flanges.

3. A car roof including a plurality of adjoining roof sheets disposed laterally of the car provided with opposed longitudinal marginal upstanding flanges and a seam cover adapted to secure the flanges of adjacent roof sheets in fixed relationship; one flange being re-bent to form a downwardly extending wall provided with a lateral flange adjacent its lower margin, said wall and

35 said lateral flange being integrally formed with said one flange and being in adjacent parallel relation with said one flange and the adjacent portion of the roof sheet, respectively.

4. A car roof including a plurality of adjacent roof sheets extending laterally of the car and provided with opposed longitudinal marginal upstanding flanges and a seam cover adapted to embrace and rigidly secure the upstanding flanges of adjacent roof sheets in parallel adjacent relationship; one of said flanges being re-bent to form an outwardly disposed and downwardly extending wall terminating in a laterally disposed edge portion, said wall and said edge portion being in adjacent parallel relation with said one of said

40 flanges and the under side of the adjacent portion of the roof sheet, respectively.

5. A car roof structure including a plurality of adjacent metal roof sheets disposed laterally of the car, a beam extending longitudinally of the

45 car in underlying supported relation with said sheets, an insulating lining in underlying relation with said sheets and supported by said beam, said sheets having opposed longitudinal marginal upstanding flanges, and a seam cover adapted to embrace and secure the upstanding flanges of

adjacent sheets in parallel fixed relationship; one of said flanges being rebent to form a downwardly extending wall terminating in a laterally disposed edge portion, said wall and said edge portion being in adjacent parallel relation with said one of said flanges and the under side of the adjacent portion of the roof sheet, respectively, said edge portion being provided with a downwardly depressed portion coincident with said beam, and means for detachably mounting said beam to the 10 under surface of said depressed portion whereby said beam will be in underlying spaced relation with said roof sheet.

6. A car roof structure including a plurality of adjoining metal roof sheets disposed laterally of the car, a plurality of spaced apart purlines extending longitudinally of the car in underlying spaced relation with said roof sheets, an insulating lining in underlying spaced relation with said roof sheets supported by said purlines, said sheets 20 having opposed longitudinal marginal upstanding flanges, and a seam cover adapted to secure the

upstanding flanges of adjacent sheets in adjacent affixed relationship; one of said flanges being rebent adjacent its upper extremity to form an integral depending wall terminating in a lateral flange, said wall extending below the plane of said roof sheets and said lateral flange being spaced downwardly from the roof sheets, and means for detachably securing said purlines in supported relation with said lateral flange.
